US00D713943S

(12) **United States Design Patent**
Luke

(10) **Patent No.:** **US D713,943 S**
(45) **Date of Patent:** **** Sep. 23, 2014**

(54) **PIPE ADAPTOR**

(75) Inventor: **Owen Edward Luke**, Kiama Heights
(AU)

(73) Assignee: **Reln Pty Ltd** (AU)

(**) Term: **14 Years**

(21) Appl. No.: **29/430,696**

(22) Filed: **Aug. 29, 2012**

(30) **Foreign Application Priority Data**

Mar. 13, 2012 (AU) 12878/2012

(51) **LOC (10) Cl.** **23-01**

(52) **U.S. Cl.**

USPC **D23/262**

(58) **Field of Classification Search**

USPC D23/259-269, 386, 393; 285/12, 63,
285/88, 405; 4/252.4; D9/435-437
